UNITED STATES PATENT OFFICE.

LUKE CHAPMAN, OF COLLINSVILLE, CONNECTICUT, ASSIGNOR TO HIMSELF
AND WILLIAM J. WOOD, OF SAME PLACE.

IMPROVEMENT IN ROTARY PUMPS.

Specification forming part of Letters Patent No. 137,055, dated March 25, 1873.

C.

To all whom it may concern:

Be it known that I, LUKE CHAPMAN, of Collinsville, in the county of Hartford and State of Connecticut, have invented certain new and useful Improvements in Rotary Pumps, applicable as well to rotary motors, meters, and blowers, of which the following is a specification, reference being had to the accompanying drawing, in which—

Figure 1 is a side elevation of the whole pump. Fig. 2 is an end elevation of the same with the head removed to show the interior. Fig. 3 is a side view of one of the rotary plungers. Fig. 4 is an end view of the same.

This invention is a new construction for retaining the cylindrical valves used in their seats.

The letter *a* indicates the outer shell formed of two intersecting hollow cylinders of equal size. *b b* are the heads for the same appropriately fastened on by screws *b¹* and having bearings and boxes *b²* for the plunger-shafts *c¹*, which are made to rotate with equal motion in opposite directions by engaging gears, one of which, *c²*, is seen. Power may be applied to either shaft. The motion is in the direction indicated by arrows. *d* is the ingress-pipe; *d'*, the exit. On the shafts *c¹* are fixed the plungers *c*, which are exactly alike, each having four parti-circular valve-seats, *c² c² c³ c³*. The valve-seats *c²* are different from the valve-seats *c³*. The latter have a depth and outline greater

than a half circle, so that they hold in the cylindrical valves *e*, which have to be slipped in endwise; the former are less than a half circle, being just deep enough to meet the projecting part of the valves contained in the other plunger. The plungers are in constant contact, except at the valve-seats, and these intervals are filled by the valves.

The water is drawn in at the pipe *f* and carried around, as indicated by the arrows, and ejected through the pipe *d'*. The plungers and valves extend entirely across the inside of the pump.

Thus it will be seen that the valves are free to rotate in their seats, and so continually present new wearing-surfaces, and at the same time are firmly held in their seats.

I claim as my invention—

1. The combination of the cylindrical valve *e* with the plunger *c* when the valve is held to the plunger by being inserted in a valve-seat of a depth and outline somewhat greater than a half circle.
2. The combination and arrangement of the two revolving plungers *c* of equal size, having valve-seats of the shapes and relative sizes shown and described, with the cylindrical valves *e*.

LUKE CHAPMAN.
